12 Claims. (Cl. 310—111)

This invention relates to electromagnetic apparatus for the generation of high voltage for accelerating substantially monoenergetic beams of charged particles. There is a need for monoenergetic beams of charged particles in many fields, including radiation chemistry, electron sterilization, and nuclear physics. Where a source of ionizing radiation takes the form of a beam of high-energy electrons, it is particularly desirable that the electron beam be monoenergetic, in order to avoid undesired side effects resulting from excessive dosage and also in order to minimize the inefficiency which results from non-uniform dosage. Moreover, the electron beams used as a source of radiation are frequently scanned by a scanning device which in general operates best upon a monoenergetic beam. Where only a limited amount of power is required, a highly monoenergetic beam of charged particles can be obtained with an electrostatic generator. However, where high powers are desired for direct-voltage acceleration of charged particles, it is necessary to use an electromagnetic voltage generator, and it may be desired to use an electromagnetic voltage generator even at lower powers. Since electromagnetic devices produce high voltage through the medium of a changing magnetic flux, the resultant voltage output is necessarily A.C., and the wave form is generally sinusoidal. A sine wave voltage can be used to produce an approximately monoenergetic beam, but in that event one can only make use of the peak of the wave. Moreover, the low-voltage portion of the sine wave is useless in any event, since the energy of low velocity electrons would be entirely lost in the electron window. Improved operation of electromagnetic devices for accelerating monoenergetic beams of charged particles may be obtained by rectifying the A.C. voltage output. This involves considerable expense in a high voltage device, since many rectifiers must be provided. Moreover, there is always the danger that one or more of the rectifiers may break down. Conservation of space in high-power devices would require the use of small rectifiers such as silicon diodes, which would still further increase the expense.

In accordance with the invention, the electromagnetic generator is caused to produce an approximately square-wave voltage output, so that the voltage is constant during the period in which charged particles are accelerated. No charged particles are accelerated when the voltage is reversed, unless a double high-voltage accelerator is used, as described in detail hereinafter. In this way the necessity for rectifiers is avoided. Since the output voltage of an electromagnetic generator is proportional to the time rate of change of the magnetic flux linked by the output coil of the generator, a square-wave voltage output is produced by causing the magnetic flux to vary in a saw-tooth manner. If the electromagnetic voltage generator is a transformer, the desired wave form is achieved by driving the primary with a current having sawtooth wave form. If the electromagnetic voltage generator is an alternator, the desired voltage wave form is achieved

by appropriate shaping of the pole faces of the rotor, so that the resultant variation in the magnetic flux is of sawtooth wave form.

The invention may be used with any electromagnetic voltage source, such as a transformer or an alternator. However, the invention is particularly useful when used with the voltage generator described and claimed in a co-pending application, Serial No. 647,915, filed March 22, 1957, and assigned to the assignee of the present invention. That is to say, the invention is particularly useful when used with electromagnetic apparatus wherein the magnetic circuit includes a core having electrically insulating properties along the lines of magnetic flux. For example, such a core may comprise ferromagnetic material having at least two gaps each crossing a substantial portion of the lines of magnetic flux, and together insulating a potential difference in excess of 10 kilovolts, the ratio of the length of each gap to the area thereof being small so as to reduce reluctance of the gap.

20 The invention may best be understood from the following detailed description thereof having reference to the accompanying drawings in which:

Fig. 1 is a diagram illustrating one embodiment of the invention in which the electromagnetic generator is a transformer;

25 Fig. 2 is a graph showing the current outputs of the alternators which drive the primary of the transformer shown in Fig. 1;

Fig. 3 is a graph showing how a sawtooth wave form is correspondingly approximated as higher frequencies are added to the primary current;

30 Fig. 4 is a graph comparing the square wave voltage output with the sawtooth wave current input;

Fig. 5 is a diagram showing an alternator adapted to 35 generate a square wave voltage in accordance with the invention; and

Fig. 6 is a somewhat diagrammatic view of a charged particle accelerator in which both half-cycles of the square-wave voltage are used to accelerate charged particles.

40 Referring to the drawings and first to Fig. 1 thereof, four alternators 1 are supported on a common shaft 2 which is driven by a motor 3. The alternators 1 are adjusted so that their frequencies are related in accordance with the Fourier series hereinafter discussed. For example, the alternators 1 may have the frequencies 60, 180, 300 and 420 cycles per second. The alternators having frequencies of 60 and 300 cycles per second should be in phase with each other, and the alternators having frequencies of 180 and 420 cycles per second

45 should be in phase with each other but 180° out of phase with the first pair of alternators. Since the alternators are driven by a common shaft, they will maintain their phase relationship once it has been properly established. The current outputs of the four alternators 1 are used to drive the primary or primaries 4 of a transformer 5. Any suitable arrangement for insuring that the relative powers delivered to the primary circuit 4 by the alternators 1 are in accordance with the aforementioned Fourier series may be employed. In the device shown in Fig. 1, the appropriate relative powers are achieved by providing a separate primary coil 4 for each alternator 1, the number of turns in each primary 4 being adjusted to give the proper power relative to the other alternators. That is to say, the power output of the alternators having frequency outputs of 180, 300, and 420 cycles per second should be, respectively, $\frac{1}{9}$, $\frac{1}{25}$ and $\frac{1}{49}$ of the power output of the alternator having a frequency of 60 cycles per second.

50 55 60 65 70 By combining the power outputs of several alternators, each having different frequencies and different power outputs, a sawtooth wave form may be approximated

in accordance with Fourier analysis. One Fourier series which generates a very accurate saw tooth wave with only a few different frequencies, owing to the rapidity with which the amplitude drops off at higher frequencies, is the following, the first four terms of which are employed in the device shown in Fig. 1.

$$I = \frac{8}{\pi^2} I_{\max} \left[\sin \theta - \frac{1}{9} \sin 3\theta + \frac{1}{25} \sin 5\theta - \frac{1}{49} \sin 7\theta + \dots - \frac{(-1)^n}{(2n-1)^2} \sin (2n-1)\theta + \dots \right]$$

The current output of each alternator is shown in the graph of Fig. 2 and the results of combining the outputs of one, two, three, and four alternators are shown in the graph of Fig. 3. As shown in the graph of Fig. 4, the voltage output of the transformer 5, which is proportional to the first derivative of the current in the primary 4 is of square-wave form.

If the electromagnetic generator operates as an alternator rather than as a transformer, as shown in Fig. 5, the required square-wave voltage output may be achieved merely by proper shaping of the pole faces 6 of the rotor. It will be recalled that the generation of a sine wave by an alternator is difficult to accomplish and is now accomplished only as a result of much empirical investigation. Similarly, the proper shape of a pole face for generating a saw-tooth wave form cannot be determined with accuracy theoretically and must be determined by experiment. However, it may be said that it would be easier to develop a rotor for generating a saw tooth wave than it has been to develop a rotor for generating a sine wave.

The principles utilized in the transformer-type embodiment of the invention shown in Figs. 1 through 4 may also be applied to the alternator-type embodiment of the invention shown in Fig. 5. That is to say, the rotor shown in Fig. 5 may be laminated, as it were, so as to comprise a series of layers, each of which is a rotor having characteristics different from those of the others; for example, the number of rotor arms might vary among layers so as to introduce different frequency components.

In the device described in connection with Figs. 1 through 4, there is only one secondary or voltage output coil 7, so that charged particles can be accelerated only during alternate half-cycles. In order to get the benefit of the other half-cycle, another embodiment of the invention may be used as shown in Fig. 6, in which a U-shaped insulating transformer core 8 is used. The primary coils 9 are wound around the bridge of the U 8, and a high voltage terminal 10, 11 is supported at each end of the U 8. The two terminals 10, 11 may be separated by an insulating "keystone" core 12 of magnetic material, which would improve the electrostatic as well as the magnetic condition of the apparatus. For more power, an additional primary circuit 13 could be added about the grounded center of this "keystone" core 12. At least one acceleration tube 14, 15 would be required for each terminal 10, 11. The two tubes 14, 15 may be so positioned that the beams 16, 17 therefrom converge on the product 18 to be irradiated, as shown in Fig. 6, or the beam from one tube could be deflected so as to produce the same effect. The two secondaries 19, 20 corresponding to the two terminals 10, 11 would be wound in opposite senses, so that the terminals 10, 11 would alternately be at high negative potential and the acceleration tubes 14, 15 would alternately deliver their electron beams 16, 17 respectively, onto the product 18.

Having thus described the method of the invention, together with several illustrative embodiments of the apparatus for carrying out the method, it is to be understood that, although specific terms are employed, they are used in a generic and descriptive sense and not for purposes of limitation, the scope of the invention being set forth in the following claims.

I claim:

1. A method of generating a high voltage suitable for the acceleration of substantially monoenergetic charged particles which method comprises generating in the same region of space a plurality of magnetic-flux components having the same or opposite orientation and each of which varies sinusoidally with time and has a frequency, amplitude and phase related to those of the other components; superimposing said magnetic-flux components upon each other so as to produce a magnetic flux which varies with time in a sawtooth manner; and converting said changing magnetic flux into a high voltage which varies with time in a sawtooth manner; and converting said changing magnetic flux into a voltage in excess of 500 kilovolts which varies with time in square wave manner.

2. A method according to claim 1 wherein said frequencies, amplitudes and phases are proportional to a sequence of initial terms in the following Fourier series:

$$\begin{aligned} & \text{Sin } \theta - \frac{1}{9} \sin 3\theta + \frac{1}{25} \sin 5\theta \\ & - \frac{1}{49} \sin 7\theta + \dots - \frac{(-1)^n}{(2n-1)^2} \sin (2n-1)\theta + \dots \end{aligned}$$

3. A method according to claim 1, wherein said frequencies, amplitudes and phases are proportional to the following terms:

$$\text{Sin } \theta - \frac{1}{9} \sin 3\theta + \frac{1}{25} \sin 5\theta - \frac{1}{49} \sin 7\theta$$

4. Apparatus for generating high voltage suitable for the acceleration of substantially monoenergetic charged particles comprising in combination a magnetic core linked by a conductive path which is adapted to generate voltage in excess of 500 kilovolts in response to changes in the magnetic flux in said magnetic core, and means for generating a changing magnetic flux in said magnetic core, the time variation of said magnetic flux being of sawtooth wave form, said magnetic core including a high voltage terminal and means for insulating said high voltage terminal from the grounded parts of said magnetic core.

5. Apparatus for generating high voltage suitable for the acceleration of substantially monoenergetic charged particles comprising in combination a magnetic core linked by a conductive path which is adapted to generate voltage in excess of 500 kilovolts in response to changes in the magnetic flux in said magnetic core, a plurality of primary coils linking said magnetic core, means for generating current in each of said primaries which current varies sinusoidally with time and has a frequency, amplitude and phase related to those of the currents in the other primaries, whereby a magnetic flux is produced in said magnetic core which varies with time in a sawtooth manner.

6. Apparatus according to claim 5, wherein said means for generating current comprises a plurality of alternators driven by a common shaft, each primary coil being energized by a separate alternator.

7. Apparatus for generating high voltage suitable for the acceleration of substantially monoenergetic charged particles comprising in combination a magnetic circuit including two high-voltage terminals and two magnetic cores having electrically insulating properties along the lines of magnetic flux, said high-voltage terminals being respectively magnetically connected to ground by said magnetic cores having electrically insulating properties along the lines of magnetic flux, said high-voltage terminals being electrically connected to ground by two conductive paths linking said magnetic cores having electrically insulating properties along the lines of magnetic flux respectively and being wound in opposite senses and adapted to generate high voltage in response to changes in the magnetic flux in said magnetic circuit, and means

for inducing a changing magnetic flux in said magnetic circuit which varies with time in a sawtooth manner.

8. Apparatus according to claim 7, wherein said magnetic circuit also includes an auxiliary magnetic core having electrically insulating properties along the lines of magnetic flux which provides a magnetic connection between said high-voltage terminals.

9. Apparatus according to claim 8, wherein said means for inducing a changing magnetic flux in said magnetic circuit includes at least one conductive path linking said auxiliary magnetic core having electrically insulating properties along the lines of magnetic flux.

10. A method of generating a high voltage suitable for the acceleration of substantially monoenergetic charged particles, which method comprises producing a magnetic flux which varies with time in a sawtooth manner; and converting said changing magnetic flux into a voltage in excess of 500 kilovolts which alternates substantially abruptly between two substantially fixed potentials.

11. Apparatus for generating high voltage suitable for the acceleration of substantially monoenergetic charged particles, comprising in combination a magnetic core

linked by a conductive path which is adapted to generate voltage in excess of 500 kilovolts in response to changes in the magnetic flux in said magnetic core, and means for producing at least one electric current which links 5 said magnetic core and which varies in time in such a manner that the resultant magnetic flux produced thereby in said magnetic core varies with time in a sawtooth manner.

12. Apparatus for generating high voltage suitable for 10 the acceleration of substantially monoenergetic charged particles comprising in combination an elongated magnetic core linked by a conductive path which is adapted to generate voltage in excess of 500 kilovolts in response to changes in the magnetic flux in said magnetic core, a magnetic circuit including said magnetic core and at least one rotor adapted upon rotation thereof to produce 15 a changing magnetic flux in said magnetic core which varies with time in a saw-tooth manner.
